MERCURY SWITCH

Carl H. Larson, Elkhart, Ind., assignor to The
Adlake Company, a corporation of IllinoisApplication October 5, 1932, Serial No. 636,288
Renewed April 30, 1934

37 Claims. (Cl. 200—112)

The principal object of this invention is to provide a mercury switch relay that may be used in place of the mechanical relays commonly used in railway signaling systems, the latter relays being 5 illustrated and described in "American Railway Signaling Principles and Practices" chapters 6 and 10, published by the Signal Section of the American Railway Association, 30 Vesey St., New York, N. Y. The use, however, of the relay is 10 obviously not limited to railway signaling systems.

Further and other objects and advantages will become apparent as the disclosure proceeds and the description is read in conjunction with the accompanying drawings, which illustrate two preferred embodiments of the invention.

In the drawings:

Fig. 1 is a vertical, sectional view of the "pull-down" embodiment of this invention, the plunger being shown in the position which it assumes 20 when the associated electromagnet is deenergized;

Fig. 2 illustrates the functioning of the relay by indicating the relationship of the plunger, mercury and contacts shortly after the electromagnet has been energized, but prior to the 25 plunger reaching its maximum depressed position;

Fig. 3 shows the plunger in its maximum depressed position.

Fig. 4 is a perspective view of the plunger with illustrative specific dimensions given;

Fig. 5 is a plan view of the relay;

Fig. 6 is a circuit diagram illustrating one environment in which the relay may be used;

Figs. 7 through 12 inclusive corresponds to Figs. 1-6 inclusive, respectively, the only difference being that the relay is of the "pull-up" type.

The illustration and description of the preferred forms of the invention are for the purpose of disclosure only and are not to be construed as imposing any limitation on the appended claims.

It has already been demonstrated in practice that mercury switch relays have certain decided advantages over the mechanical relays heretofore commonly used in railway signaling systems. The fact that all electrical contacts of a mercury switch relay are hermetically sealed within a glass envelope and in consequence are not subject to the deteriorating effects of the atmosphere is but one of the cardinal advantages of this type of relay.

Other advantages which may be briefly mentioned reside in the elimination of bearings and movable parts; the constant and extremely low contact resistance unaffected by temperature changes of 40° below zero to 300° above zero; the lack of wear on the contact material; the noiseless 55 operation on both alternating current and direct

current; the economy of space due to compact mounting; and the complete elimination of the necessity for inspection and maintenance.

The mercury switch relay of this invention is designed to offer greater economies in the cost of 5 operation and manufacture and to provide greater reliability in use.

Referring now to the drawings, and particularly to Figs. 1 to 6 inclusive, there is illustrated a preferred embodiment of the invention in which 10 the electromagnetically actuated plunger is of the "pull-down" type. In other words, when the relay is de-energized, the plunger floats on the mercury and establishes electrical contact between two electrodes and when the relay is energized, 15 the plunger is drawn downwardly to uncover one of those electrodes and establish electrical connection between the other electrode and a third electrode.

The relay comprises a glass envelope 20, 20 evacuated and filled with a suitable inert gas such as helium or hydrogen, after which it is sealed off at 21. Three electrodes 22, 23 and 24 are pinch sealed, as shown at 25, into the base of the envelope and project to varying heights into the 25 interior of the envelope.

The envelope 20 may be made of any suitable glass, low expansion boro-silicate glass or glass of similar quality being preferred. The electrodes 22, 23 and 24 may be tungsten, molybdenum, copper-coated nickel alloy wire, or any other suitable material that will form a suitable seal with the glass envelope.

A quantity of mercury 26 is sealed into the switch envelope and is in constant electrical contact with the electrode 22. The electrode 23 is insulated from the mercury by a glass sleeve 27 to a height less than the height of the electrode 23 so as to leave a portion of the electrode 28 exposed to the mercury in the envelope. The electrode 24 is similarly insulated by a glass sleeve 29 leaving a portion 30 of the electrode bare. In the particular switch illustrated, the electrodes 22, 23 and 24 rise to heights of $\frac{3}{8}$ ", $2\frac{1}{8}$ " and $3\frac{1}{8}$ ", respectively, and a sufficient quantity of mercury 45 is used to cover the electrode 23 when the relay is de-energized.

A plunger or displacer 31 placed in the envelope before it is evacuated, filled with an inert gas and sealed off, is adapted to reciprocate within 50 the envelope under the influence of an electromagnet, generally indicated at 41, for the purpose of changing the mercury level and selecting which one of the electrodes 23 and 24 shall be in electrical contact with the electrode 22. The 55

plunger 31 consists of a sleeve 32 of magnetic material, such as Swedish iron, although it may be made of any suitable magnetic material. The sleeve 32 has an external diameter slightly less than the internal diameter of the envelope, this difference being substantially bridged by lugs 33 on the top and bottom of the plunger to guide the plunger in its vertical movement. Springs 34 and 35 are provided at the top and bottom, respectively, of the plunger to protect the envelope from injury due to rough handling. The upper spring, preferably, limits the upward movement of the plunger to insure uniform performance of the relay but having an excess of buoyancy, the plunger will always rise to its proper position, and in addition the pick-up and drop-away voltages are brought closer together. The top of the plunger 31 is rounded off at 36 and provided with a socket 37 into which an inverted cup-shaped element or cap 38 is adapted to be adjustably seated. The adjustability of the cap 38 permits correction to be made for manufacturing tolerances, so that the relay will have the required characteristics. It is not essential that the cap 38 be of magnetic material, but it is preferred.

The cap being concentrically mounted with respect to the sleeve 32 is directly over the electrode 23 which is located on the axis of the switch. The electrode 24 fits in a slot 39 in the wall of the sleeve 32, the slot extending from the socket 37 at the top of the plunger down to the base of the plunger. This slot in addition to furnishing a place into which the electrode 24 may fit, and permitting the mercury to rise freely on the outside of the cap without entrapping gas, also increases the efficiency of the relay about 40% when the latter is operated on alternating current. This is apparently explained by the fact that the slot prevents the flow of induced currents in the plunger resulting from the constantly changing direction of the magnetic field. The slot also permits a compact arrangement of the switch parts within the envelope.

The electromagnet which operates the relay consists of a laminated yoke 40 between the arms of which a spool 41 with its winding 42 is mounted. Within the spool 41 and surrounding the switch envelope are pole sleeves 43 and 44 suitably secured to the laminated yoke 40 and made of ferro-magnetic material. The air gap indicated at 45 which separates the pole pieces is bridged by the plunger 31 when the electromagnet is energized and the plunger thus acts as an armature of the magnet.

In operation, when the electromagnet is de-energized, the plunger 31 floats upon the mercury and assumes the position shown in Fig. 1. In this position, the electrode 23 is covered by mercury due to the relationship of the height of the electrode, the displacing effect of the plunger, and the quantity of mercury within the tube.

When the relay is energized, the plunger sinks in the mercury in its effort to close the air gap between the pole pieces 43 and 44 and first uncovers the electrode 23, as shown in Fig. 2. The cap 38, as will be seen, forms a gas trap which forces the mercury away from the bared portion 28 of the electrode and completely breaks the electrical circuit between the electrode 22 and the electrode 23 before the mercury level reaches a height on the outside of the cap sufficient to establish electrical connection between the electrode 24 and the electrode 22. This occurs, however, upon further depression of the plunger, as will be seen from Fig. 3. The cap 38 being made

of impervious material holds the mercury away from the central electrode as long as the plunger is lowered.

When the relay is used to transfer a load from one source of current to another, the electrode 22 is connected to the load and the electrodes 23 and 24 are connected to one side of the two sources, respectively. This is best illustrated in Fig. 6 which is a circuit diagram showing a railway signal 46 normally operated on alternating current but adapted to be operated on direct current whenever the former falls below a predetermined standard.

The alternating current is usually supplied from a power line and is reduced in voltage by a transformer 47, the secondary coil of which is in series with the signal. A local battery 48 is provided at suitable points along the line so that upon failure of the alternating current, the signal will be operated from the local circuit.

To better illustrate the use of the relay in such a circuit, the relay 49 in Fig. 6 has been shown as a mechanical relay, but it will be understood that the coil 50 corresponds to the coil 42 of the mercury switch relay; the armature 51 to the plunger 31; the conductor 52, which connects the armature to the signal 46, corresponds to the electrode 22; the contact 53, to the electrode 23; and the contact 54 to the electrode 24. The spring 55 causes the armature 51 to contact with the contact 53 when the coil 50 is de-energized and, therefore, corresponds to the buoyancy of the mercury which maintains the plunger 31 in elevated position when the coil 42 is deenergized. Thus, whenever the voltage in the secondary coil of the transformer 47 falls below a predetermined standard, the spring 55 in the mechanical relay, Fig. 6, (or the buoyancy of the mercury in the mercury switch relay, Figs. 1-3) causes the alternating current circuit to be broken at 54 (the electrode 23 Figs. 1-3) and the direct current circuit to be made at 53 (the electrode 24, Figs. 1-3). If later the alternating current picks up to its predetermined standard, the armature 51 is pulled away from the contact 54 and the alternating current circuit is reestablished.

In Figs. 7-12, a second preferred embodiment of the invention is shown. This embodiment differs from the relay just described only in that it is of the "pull-up" type, i. e. the plunger is pulled out of the mercury when the relay is energized instead of being lowered into the mercury as was the case of the relay shown in Figs. 1-6 inclusive. Due to the difference in the mode of operation of the two types of relays, the position of the air gap, the length of the electrodes and the dimensions of the plunger are somewhat different. The operation of the switch, however, is substantially the same.

As seen in Figs. 7-9 inclusive, the pole sleeves 56 and 57 provide an air gap 58 adjacent the top of the switch envelope which is adapted to be closed by the plunger 59 when the coil 60 is energized. The plunger 59, except for its dimensions, is identical in every respect to the plunger 31 shown in Figs. 1-4 inclusive, and, therefore, need not be specifically described.

The electrodes 61, 62 and 63 correspond to the electrodes 22, 23 and 24, respectively, of the "pull-down" relay and, in the switch shown, rise to heights of $\frac{3}{8}$ ", $1\frac{1}{4}$ " and $1\frac{1}{4}$ ", respectively, within the envelope. A sufficient quantity of mercury 64 is placed in the envelope to cover the electrode 63 when the switch is deenergized.

It is apparent from Figs. 7 to 9 inclusive that

when the relay is deenergized, the electrode 62 projects into the interior of the cap 65 and is out of contact with the mercury whereas the electrode 63 is covered with mercury and establishes electrical connection between the electrode 61 and 63. When the relay is energized, the plunger is drawn upwardly and when it reaches the position shown in Fig. 8, completely uncovers electrode 63 while still maintaining the electrode 62 out of contact with the mercury. As the plunger rises higher in the envelope, the cap 65 is lifted above the top of the electrode 62 and allows mercury to come in contact with the electrode 62 to establish an electrical connection with the electrode 61.

The operation of the switch is diagrammatically illustrated in Fig. 12 which is similar in all respects to the diagram of Fig. 6 with the exception that the armature 51 in this case falls by gravity 20 on the contact 53 when the alternating current fails instead of being raised by a spring 55 (Fig. 6) or the buoyancy of the mercury (Figs. 1-3) as in the "pull-down" type of relay.

In addition to the specific data which have already been given with respect to the height of the electrodes, the quantity of mercury, etc. which, it will be understood is for the purpose of disclosure only, specific dimensions of the plungers 31 and 59 have been indicated in Figs. 4 and 30 10, respectively.

In both embodiments of the invention, the distance between the pole pieces is $\frac{5}{8}$ " and the switches are located in a position so that the plunger in the "pull-down" switch is $\frac{1}{4}$ " above the lower pole piece in the deenergized position and on the "pull-up" switch, the plunger is $\frac{1}{4}$ " above the upper pole piece in the deenergized position. The coils for operating the relays are 40 wound with 15 gauge enameled wire, 260 turns, drawing 2 watts at 10 volts. The pick up with this rating of coil is 7 volts for the "pull-down" type and 4.9 volts for the "pull-up" type, which indicates that the "pull-up" type is approximately 45 30% more efficient.

In both embodiments of the invention, it will be noted that the cap gives additional buoyancy to the plunger by reason of the gas trap that it forms when in its lowered position. By this construction, more of the mass of the plunger may be concentrated in the outer sleeve where operating efficiency is increased by lessening the air gap between the armature and the pole pieces. Approximately 55 30% is gained in efficiency by constructing the plunger in this way.

It will be understood that many of the advantages of this invention may be utilized in a two electrode switch by eliminating one or the other 60 of the intermittently covered electrodes.

To protect the plunger cap against the deteriorating effects of arcing when the switch is used with high amperage, the interior of the cap may be lined with a ceramic sleeve in a manner well 65 known to the art.

The plunger sleeve may be protected from arcing at the outside electrode by applying a small amount of insulation material to the sleeve adjacent the bared portion of the electrode and then baking it to insure its firm adherence to the sleeve. 70

The invention may be variously embodied within the scope of the appended claims.

The use of the expression "intermittently immersed" in several of the claims is intended to in- 75

clude immersion of the electrodes at either regular or irregular intervals of time.

What I claim, therefore, is:

1. In an electro-magnetic mercury switch, the combination of a vertical switch envelope having a quantity of mercury therein, a plurality of electrodes sealed through the envelope, one being constantly in contact with the mercury and two being alternately, but never simultaneously, in contact therewith, a plunger floating on the mercury and determining, by the amount of mercury that it displaces which of the two intermittently immersed electrodes is in contact with the mercury, electromagnetic means for changing the amount of mercury displaced by the plunger, said plunger being in the form of a sleeve provided with an inner cap adapted to fit over one of the two intermittently covered electrodes when the plunger is in its lowered position and cause the electrode to be uncovered. 10 15

2. In an electromagnetic mercury switch, the combination of a vertical switch envelope having a quantity of mercury therein, a plurality of electrodes sealed through the envelope, one being 20 constantly in contact with the mercury and two being alternately, but never simultaneously, in contact therewith, a plunger floating on the mercury and determining, by the amount of mercury that it displaces which of the two intermittently 25 immersed electrodes is in contact with the mercury, electromagnetic means for changing the amount of mercury displaced by the plunger, said plunger comprising a sleeve provided with a pocket arranged above one of the two intermittently 30 covered electrodes and adapted, when the plunger is lowered, to trap gas within the cap and force the mercury from the electrode. 35

3. In an electromagnetic mercury switch, the combination of a vertical switch envelope having 40 a quantity of mercury therein, a plurality of electrodes sealed through the envelope, one being constantly in contact with the mercury and two being alternately, but never simultaneously, in contact therewith, a plunger floating on the mercury and determining, by the amount of mercury that it displaces which of the two intermittently 45 immersed electrodes is in contact with the mercury, electro-magnetic means for changing the amount of mercury displaced by the plunger, said plunger comprising a cylindrical sleeve having 50 a smaller sleeve closed at the top, carried interiorly of the first named sleeve, and adapted to force mercury from one of the two intermittently covered electrodes when in its lowered position. 55

4. In an electromagnetic mercury switch, the combination of a vertical switch envelope having a quantity of mercury therein, a plurality of electrodes sealed through the envelope, one being constantly in contact with the mercury and two being alternately, but never simultaneously, in contact therewith, an electromagnetically actuated plunger floating on the mercury and adapted to control the level of the mercury in the envelope, said plunger comprising a sleeve of magnetic material having an external diameter slightly less than the internal diameter of the envelope, and carrying an inverted cup-shaped element adapted to form a gas trap over one of the intermittently 60 immersed electrodes when the plunger is in its lowered position to thereby uncover that electrode. 65

5. In an electromagnetic mercury switch, the combination of a vertical switch envelope having a quantity of mercury therein, a plurality of elec- 70 75

- trodes sealed through the envelope, one being constantly in contact with the mercury and two being alternately, but never simultaneously, in contact therewith, an electromagnetically actuated 5 plunger floating on the mercury and adapted to control the level of the mercury in the envelope, said plunger comprising a sleeve of magnetic material and being equipped with a pocket, closed at the top, for creating a gas trap over 10 one of the intermittently covered electrodes when the plunger is in its lowest operative position, thereby uncovering the one electrode and establishing electrical connection with the other.
6. In a mercury switch, a switch envelope, a 15 quantity of mercury therein, a pair of electrodes sealed through the envelope, and a plunger for making and breaking an electrical circuit through the electrodes, said plunger having an inner, downwardly projecting impervious cap adapted 20 to telescope over one of the electrodes and hold mercury from said electrode when the plunger is in lowered position.
7. In a mercury switch, a switch envelope, a quantity of mercury therein, a pair of electrodes 25 sealed through the envelope, and a plunger for making and breaking an electrical circuit through the electrodes, said plunger having an inner, downwardly projecting impervious cap adapted to increase the buoyancy of the plunger when 30 depressed.
8. In a mercury switch, a vertically supported switch envelope, a quantity of mercury therein, a pair of electrodes sealed through the envelope and adapted to complete an electrical circuit 35 when bridged by the mercury, an electromagnetically actuated plunger in the envelope for manipulating the mercury to change the condition of the circuit, said plunger comprising an outer sleeve, the external diameter of which is slightly 40 less than the internal diameter of the envelope, and an inner sleeve, closed at the top, adapted to form an impervious gas trap over one of the electrodes when the plunger is in its lowered position to thereby hold mercury from the electrode 45 and maintain the electrical circuit open.
9. A plunger for use in a switch of the class described comprising an outer sleeve of substantially uniform external diameter, and an inner sleeve, closed at the top, and impervious, 50 mounted in said first named sleeve.
10. A plunger for use in a switch of the class described comprising a sleeve of magnetic material having a substantially impervious inverted cup-shaped sleeve interiorly mounted in the first 55 named sleeve.
11. A plunger for use in a switch of the class described comprising a sleeve of magnetic material having an inverted cup-shaped sleeve interiorly mounted in the first named sleeve and 60 longitudinally adjustable relative to said sleeve.
12. A plunger for use in a switch of the class described comprising an outer sleeve of magnetic material having a uniform external diameter slightly less than the internal diameter of the 65 switch envelope, guide lugs on the sleeve for maintaining it at the appropriate distance from the envelope, and an inverted cup-shaped sleeve of impervious material interiorly mounted in the first named sleeve.
13. A plunger for use on a switch of the class described comprising a sleeve of magnetic material having an inverted cup-shaped sleeve of impervious material interiorly mounted in the first 70 named sleeve, said outer sleeve having a longi-

tudinal slot extending to a point above the bottom of the cup-shaped inner sleeve.

14. A plunger for use in a mercury switch comprising a cylindrical sleeve of magnetic material closed at its upper end except for a socket opening and a slit extending from one side of the opening down to the bottom of the sleeve, and an inverted cup-shaped member adjustably seated in said socket opening. 5

15. In a mercury switch, a switch envelope, a 10 quantity of mercury therein, a pair of electrodes sealed through the envelope, and a plunger for making and breaking a circuit through the electrodes, said plunger comprising an armature of magnetic material and an inverted cup-shaped 15 member of impervious material adapted to dip in the mercury.

16. A plunger for use in a mercury switch comprising an armature of magnetic material and an inverted cup-shaped element of impervious material carried by the armature to increase the 20 buoyancy of the plunger.

17. In a mercury switch, a switch envelope, a quantity of mercury therein, a pair of electrodes sealed through the envelope, and a plunger for 25 making and breaking a circuit through the electrodes, said plunger comprising an armature of magnetic material, and being equipped with means for creating an impervious gas trap over one of the electrodes to hold mercury from that 30 electrode when the plunger is lowered.

18. A plunger for use in a mercury switch, having a portion made of magnetic material for responding to a magnetic field and a portion adapted to form an impervious gas trap when closed at 35 the bottom by mercury.

19. In a mercury switch, a switch envelope, a quantity of mercury therein, a pair of electrodes sealed through the envelope, and a plunger for making and breaking a circuit through the electrodes, said plunger comprising an armature of 40 magnetic material and including an inverted cup-shaped member of impervious material adapted to telescope over one of the electrodes to force mercury from that electrode when the plunger 45 is lowered.

20. In an electromagnetic switch, the combination of a vertical switch envelope having a quantity of mercury therein, a plurality of electrodes sealed through the envelope, one being constantly 50 in contact with the mercury and two being alternately, but never simultaneously, in contact therewith, a plunger floating on the mercury and determining by the amount of mercury that it displaces which of the two intermittently immersed 55 electrodes is in contact with the mercury, electromagnetic means for changing the amount of mercury displaced by the plunger, said plunger including means for forcing mercury from one intermittently immersed electrode when the other 60 of said electrodes is in contact with the mercury.

21. A standby relay for transferring a load from a primary source of electrical energy to an auxiliary source whenever the former falls below a pre-determined value, said relay comprising an 65 electromagnetic switch having front and back contacts hermetically sealed from the atmosphere and adapted to be connected one to each of said sources, mercury associated with said contacts, and means controlled by the electromagnet for 70 selecting one of the contacts to be placed in direct physical contact with the mercury.

22. In a mercury switch of the class described, a vertical switch envelope, a quantity of mercury therein, spaced electrodes in the envelope, two 75

being at different heights and one of the two being normally in contact with the mercury, and means for bringing the other of the two electrodes into contact with the mercury and substantially simultaneously uncovering the first, said means including a displacer for shifting the mercury level, and means for forming a gas trap over the first-mentioned electrode.

23. In a mercury switch of the class described, a vertical switch envelope, a quantity of mercury therein, spaced electrodes in the envelope, two being at different heights and one of the two being normally in contact with the mercury, and means including a mercury displacer for forcing mercury from the normally covered electrode and causing mercury to contact with the other of the two electrodes.

24. In a mercury switch of the class described, a vertical switch envelope, a quantity of mercury therein, spaced electrodes in the envelope, one being normally in contact with the mercury and another being normally out of contact with the mercury, and means for reversing the relation of the said electrodes to the mercury, said means including a displacer equipped with means for forming a gas trap over one of said electrodes when the displacer is in its lowered position.

25. In a mercury switch of the class described, a vertical switch envelope, a quantity of mercury therein, spaced electrodes in the envelope, one being normally in contact with the mercury and another being normally out of contact with the mercury, and means for reversing the relation of the said electrodes to the mercury, said means including a displacer equipped with means for forming a gas trap over one of said electrodes when the displacer is in its lowered position, said other electrode being outside of the gas trap and subject to the mercury displacement action of the displacer.

26. In a mercury switch of the class described, a vertical switch envelope, a quantity of mercury therein, a displacer for shifting the mercury, spaced electrodes in the envelope, two being at different heights and positioned so that one is above the mercury level and the other immersed in the mercury when the plunger is in raised position, and means for forcing mercury from the immersed electrode when the displacer is lowered.

27. In a mercury switch of the class described, a vertical switch envelope, a quantity of mercury therein, a displacer for shifting the mercury, spaced electrodes in the envelope, two being at different heights and positioned so that one is above the mercury level and the other immersed in the mercury when the plunger is in raised position, and means carried by the displacer for forcing mercury from the immersed electrode when the displacer is lowered.

28. A switch envelope for use in a mercury switch of the type in which a displacer is magnetically controlled for manipulating mercury within the envelope, said envelope comprising a tubular body having at least three electrodes sealed through the base thereof, two of the said electrodes projecting upwardly within the envelope and both being surrounded by insulating sleeves for a portion of their lengths.

29. A switch envelope for use in a mercury switch of the type in which a displacer is magnetically controlled for manipulating mercury within the envelope, said envelope comprising a tubular body having at least three electrodes sealed through the base thereof, two of the said electrodes projecting upwardly within the envelope and both being surrounded by insulating sleeves for a portion of their lengths.

veloped and both being surrounded by insulating sleeves for a portion of their lengths, one of the insulating sleeves being shorter than the other.

30. In an electromagnetic mercury switch, a combination of a vertical switch envelope having a quantity of mercury therein, spaced electrodes in the envelope, an electro-magnetically actuated plunger floating on the mercury and adapted to control the level of the mercury, and a spring above the plunger adapted to normally hold the plunger lower than its normal floating position.

31. In a mercury switch of the class described, a switch envelope, a mercury fill, a plurality of spaced electrodes sealed through the base of the envelope and projecting upwardly, one being substantially along the axis of the envelope, and another being adjacent to the side wall of the envelope, a displacer telescoped over the central envelope for shifting the mercury level, said displacer having a longitudinal slot receiving the side electrode whereby the overall dimensions of the switch may be kept to a minimum.

32. A standby relay for transferring a load from a primary source of electrical energy to an auxiliary source whenever the former falls below a pre-determined value, said relay comprising an electromagnetic switch having front and back contacts hermetically sealed from the atmosphere and adapted to be connected one to each of said sources, mercury associated with said contacts, and means controlled by the electromagnet for selecting one of the contacts to be placed in direct physical contact with the mercury, said means including a displacer responsive to the electromagnet for changing the level of the mercury.

33. In a mercury switch, a switch envelope, a quantity of mercury therein, a pair of electrodes sealed through the envelope, and a plunger for making and breaking the circuit through the electrodes, said plunger comprising an armature of magnetic material and including an inverted cup-shaped member adapted to telescope over one of the electrodes to force mercury from that electrode when the plunger is lowered, the other electrode being surrounded by an insulating sleeve for a portion of its length and being responsive to the mercury level outside of the plunger.

34. In a mercury switch of the class described, a vertical envelope, a charge of mercury in the envelope, a magnetically controlled displacer for changing the mercury level, a plurality of electrodes within the envelope, one of which is responsive to the mercury level on the outside of the displacer, said displacer having means for forming a gas trap over another of said electrodes to force mercury away from said electrode when the displacer is lowered.

35. A standby relay for use in railway signaling systems for transferring a load from a primary source of electrical energy to an auxiliary source whenever the former falls below a predetermined value, said relay comprising an electromagnetic switch having independent front and back contacts hermetically sealed within a vertical switch envelope and adapted to be connected one to each of said sources, mercury associated with said contacts, and means controlled by the electromagnet for selecting one of the contacts to be placed in direct physical contact with the mercury, said means including a displacer responsive to the electromagnet for changing the level of the mercury.

36. A standby relay for use in railway signaling systems for transferring a load from the pri-

mary source of electrical energy to an auxiliary source whenever the former falls below a pre-determined value, said relay comprising an electro-magnetic switch having independent front 5 and back contacts hermetically sealed within a vertical switch envelope and adapted to be connected one to each of said sources, mercury associated with said contacts, and means controlled by the electromagnet for selecting one of the contacts to be placed in direct physical contact with the mercury, said means including a displacer responsive to the electromagnet for lowering the 10 level of a portion of the mercury fill and raising

the level of another portion whenever the displacer is moved downwardly.

37. In a mercury switch of the class described, a switch envelope, a mercury fill, a plurality of spaced electrodes sealed through the base of the 5 envelope at least one of which is adjacent to the side wall of the envelope, a displacer for shifting the mercury level, said displacer having a longitudinal slot receiving said one electrode whereby the overall dimensions of the switch 10 may be kept to a minimum.

CARL H. LARSON.
